Primary Examiner — Ian Simmons*Assistant Examiner* — Charles D Hanson(74) *Attorney, Agent, or Firm* — Workman Nydegger(57) **CLAIM**

The ornamental design for an adhesive phone accessory, as shown and described.

DESCRIPTION

The file of this patent contains at least one photograph executed in color. Copies of this patent with color photographs will be provided by the Office upon request and payment of the necessary fee.

FIG. 1 is a perspective view of an adhesive phone accessory showing my new design;

FIG. 2 is a top plan view thereof;

FIG. 3 is a front elevational view thereof, the left side, right side, and back elevational views thereof being identical thereto; and,

FIG. 4 is a bottom plan view thereof.
